ORTHODONTIC APPLIANCE

Joseph D. Berke, New York, N. Y.

Application February 26, 1944, Serial No. 524,076

10 Claims. (Cl. 32—14)

1

This invention relates to the art or technique of orthodontia.

The prime object of my invention centers about the improving of the technique of modern orthodontia and the provision of an improved orthodontic appliance for treating malocclusion.

In the treatment of malocclusion, different teeth of a given denture are required to be subjected to forces differing both in magnitude and direction for accomplishing various movements, differing with the nature or degree of dislodgment of the teeth from the arch line and the plane of occlusion. In general, a tooth or the teeth may require an uprighting movement for correction for mesial inclination (inclination sidewise with reference to the medial plane), an uprighting movement for correction for distal inclination (inclination backwards with reference to the arch line), a bodily movement to arch aligning position, an elevation or depression movement towards the occlusion plane, a rotative movement for axis orientation, or a combination of two or more of these corrective movements.

The orthodontic appliance commonly employed in modern orthodontia in the treatment of malocclusion comprises a ribbon or equivalent arch mechanism. This mechanism consists of a bracket on a tooth enveloping band and a suitably anchored arch wire or ribbon seated in a suitably slotted or receptacled part of the bracket. Ligatures anchored to the band are connected by the orthodontist to the arch wire and this connection is made so as to apply, both directionally and magnitudinally, the proper corrective forces to the tooth. The ligature wire also serves to hold the arch wire seated in or to the bracket. To make effective the various corrective forces referred to, the arch wire also has to be bent at selected points along its length. Thus, for example, for a correction for mesial inclination, the arch wire has to be bent to an inclined position in a vertical plane, so as to be tensioned against spaced points on the bracket and thereby exert the required turning torque on the tooth. Many improvements have been suggested or devised for this technique, but in all of them, so far as I am aware, the arch wire has to be manually locked to the bracket so as to be firmly seated therein and the arch wire has to be manually bent or adjusted to the individual teeth of each denture, and in most cases the use of ligature wires has to be resorted to.

The orthodontia technique employing these appliances of the prior art is most difficult both

for the orthodontist and the patient. Besides obviously requiring great skill, even after proper diagnosis, to fairly accurately predetermine, both for magnitude and direction, the corrective forces to be applied, the work of bending and adjusting the arch wire to shape and of properly positioning and tieing in the ligature wires is hard and tedious to the doctor and trying and tiring to the patient. Moreover, this work and the initial application of the orthodontic appliance is based upon a static diagnosis whereas a dynamic condition is brought about as soon as the teeth move responsive to the applied forces. The result is that the appliance is soon out of adjustment, and not being built for self-correction or automatic adjustment, frequent trips to the doctor are required or readjustments, to the discomfort both to the orthodontist and the patient.

20 In the orthodontia technique of my present invention, the proper corrective forces come into play by dint of the inherent or designed structure of the orthodontic appliance rather than by the manner in which the appliance is applied to the patient and adjusted. The orthodontic appliance of the present invention also comprises a band bracket and an arch wire, without more, however, and both of special construction, so designed that the following results 25 and advantages are accomplished:

1. The arch wire is directly mountable on and receivable by the bracket, without prebending or distortion or any other adjustment and without the use of ligature wires or other locking or connecting means;

2. The forces come into play by the relationship automatically assumed between the arch wire and the bracket by dint of their structure; and these forces that become applicable are substantially correct, both directionally and magnitudinally, for producing the desired corrective movement or movements of the teeth; and

3. The forces vary in the right directions and in the right magnitudes as the corrective movements take place in the use or wearing of the appliance, whereby self-adjustment takes place.

As a corollary, just as no adjustment is needed in initially applying the device to the denture, so no readjustments are required as the corrective movements of the teeth take place.

To the accomplishment of the foregoing objects and such other objects as may hereinafter appear, my invention relates to the orthodontic appliance as sought to be defined in the appended claims and as described in the following

2

specification taken together with the accompanying drawing, in which:

Fig. 1 is a perspective view of a band and bracket made according to the present invention;

Fig. 2 is a view thereof taken in cross-section in the plane of the line 2—2 of Fig. 1;

Fig. 3 is a top plan view thereof;

Fig. 4 is a front view showing the inter-relation between the said band and bracket and a component part or segment of the arch wire of the present invention used therewith;

Fig. 5 is a view showing a length of the arch wire used;

Fig. 6 is a view of the latter taken in cross-section in the plane of the line 6—6 of Fig. 5;

Fig. 7 is a plan view of a denture showing the orthodontic appliance of the present invention applied thereto for producing a number of types of corrections;

Fig. 8 is a front view of the orthodontic appliance showing the same applied for correcting a mesial inclination;

Fig. 9 is a side view of the latter with parts shown in section; and

Fig. 10 is an enlarged view of a development of the central and lateral incisors of Fig. 7 showing the orthodontic appliance and exemplifying certain principles of operation thereof.

Referring now more in detail to the drawing and having reference first to Figs. 1 to 4 thereof, the orthodontic appliance of the present invention comprises a button bracket which may be attached to or formed part of a tooth band as shown in Figs. 1 to 3 of the drawing and generally designated as B, and a resilient and flexible arch wire which preferably embodies a construction as shown in Figs. 5 and 6 of the drawing and generally designated as A, the said arch wire A and the button bracket B being designed to cooperate or become interrelated as generically shown in Fig. 4 of the drawing and as exemplified by denture application in the remaining figures of the drawing.

Referring now to Fig. 4 of the drawing, which shows a unit segment or component part of the orthodontic structure, the resilient and flexible arch wire A is provided in one of its segments with a loop member generally designated as l, the said loop member being receivable by the button b of the bracket B. The loop member l is formed by top and bottom component elements or strands 20 and 22 joined or connected together at spaced points as by means of the links 24 and 26 which latter may be suitably brazed or welded to the strands 20 and 22. The button b comprises a shank 28 and a head 30. The elements of the button b and the elements of the loop l are elongated and preferably in the horizontal direction as clearly shown in Fig. 4. With this construction the loop member l when slipped over the head 30 of the button b, distends or expands into the position shown in full lines in Fig. 4, and then contracts itself into engagement with the shank 28 of the button b as shown by the dotted lines in Fig. 4, the normal configuration of the loop, the resiliency of the elements thereof and the anchorage of the strands thereof at the joined points or links 24 and 26, all contributing to causing the loop member and particularly the strands thereof to come into tensioning engagement with the opposite sides of the button shank and with the button head to apply the desired corrective

forces, all as will be further described more in detail hereinafter.

Referring now to Figs. 1 to 3 of the drawing, the button bracket B is fixed to a tooth encircling band 32 as by being brazed or welded thereto and in such a position as to occupy the center of the labial surface of the tooth when the band is applied to the tooth. The shank 28 of the bracket may also be provided with one or more orifices 34 depending upon the linear dimensions of the button b.

The brackets may be made in a number of sizes particularly with respect to the linear button dimensions depending upon the tooth to which it is to be applied and the degree of correction needed therefor.

The arch wire may be constructed as best shown in Figs. 5 and 6 of the drawing. This arch wire A may comprise two parallel wire strands 36 and 38 connected along their lengths at selected points such as 40, 40 to form a series of loops l, l each embodying a construction and formation such as shown and such as has been described in connection with Fig. 4 of the drawing. The arch wire may be suitably made from stainless steel or from gold wire and at any desired gauge. The resulting construction is a resilient and flexible arch wire having a series of component parts each in the form of a loop member capable of functioning in the manner depicted in Fig. 4 of the drawing and more particularly described presently.

From the construction thus far described, it will be evident that the arch wire A is directly mountable on and receivable by a number of brackets such as B, without necessity of pre-bending or distorting the same or supplying any other adjustment and without the use of any ligature wires or other locking or connecting means. After the bracket bands are applied to the patient's tooth, the arch wire anchored at its ends in a conventional manner is then applied by merely slipping the component loops l, l over the heads b, b of the band brackets, after the manner depicted in Fig. 4 of the drawing. Each applied loop member distends or expands itself as it is slipped over the head of its button and contracts itself into engagement with the shank of such button. Immediately this is done, each used loop member becomes locked or held in position by its button head and becomes effective to apply the corrective forces by its engagement with its associated button shank and also with its button head.

In Fig. 7 of the drawing, I show the arch wire A applied to a denture D and to a number of band brackets B, B mounted on various teeth of the denture. In this figure I illustrate a number of different types of teeth dislodgments requiring different characters of correction. Thus the central incisors t' and t' (also shown in Fig. 10 of the drawing) are shown as requiring an uprighting correction for a mesial inclination (shown in Fig. 10) and also a rotative movement for axis orientation (as shown in Fig. 7). The second bicuspid, left, t³ is shown as requiring a bodily movement to arch-aligning position and the second bicuspid, right, t⁴ is shown requiring a similar correction but one of larger degree. The application of the principles of the invention to the production of these different corrections will, it is believed, exemplify the basic principles of operation of the present construction. In Fig. 7 the arch wire A is also shown anchored on the

first molars t^5 and t^6 by means of the usual anchor clamps 42 and 44.

Referring now to Figs. 8 and 9 of the drawing, I show the appliance as it is mounted on a central incisor tooth t' . These figures are further explanatory of the interrelation described in connection with Fig. 4 of the drawing and show the same as it is operative on a tooth requiring a correction for mesial inclination. The forces active here will become clearer from a consideration now of the showing depicted in Figs. 7 and 10 of the drawing.

The central incisor t' as shown in Fig. 7 and Fig. 10 of the drawing requires, as aforesaid, a correction for mesial inclination and for axis orientation. As shown in Fig. 10 of the drawing, after the loop l is slipped over the button of the bracket, the opposite strands 20 and 22 thereof contract and come into engagement with the opposite sides 46 and 48 of the button shank 28. The inclination of the tooth and the corresponding inclination of the button shank, which latter is extended in a horizontal direction, causes the remaining distention or expansion of the loop as shown in Fig. 10, with the result that the opposite strands 20 and 22 of the loop exert a light torque pressure on the opposite sides of the shank 28 creating the turning torque indicated by the two arrows 50 and 52. It will be noted that the torque exerted on opposite sides of the shank is in the same rotative direction and in a direction for correcting for the mesial inclination of the incisor t' . In this figure is also shown the adjacent central incisor t^2 , which, however, is shown to require a smaller correction for mesial inclination. Here it will be noted that because of the correspondingly smaller inclination of the button shank 28' and the resulting smaller distortion or distention of the loop l' , the turning torque forces represented by the arrows 54 and 56 are quantitatively smaller than those operating upon the tooth t' . Thus from a consideration of Fig. 10 of the drawing, it will be apparent that by virtue of the inherent or designed construction of the bracket buttons and the arch wire, not only do the corrective forces come into play automatically as soon as the arch wire is applied, but that for corrections for mesial inclination the forces that become operative automatically are correct not only directionally but magnitudinally to correspond to the existing corrective needs. The pressures or forces required physiologically are extremely light and steady; the natural resiliency and flexibility of the arch wires and their component loops and the relationship between the component loops and the bracket buttons are such as to produce this very light yet steady pressure.

From a consideration of Fig. 10, it will be also evident that the orthodontic appliance is self-adaptable for the dynamic condition which exists, and that it does not require the continued adjustments which characterize orthodontic appliances now in use. From a comparative consideration of the two central incisors t' and t^2 , it will be seen that as the tooth moves in response to the turning torque forces from a position such as is assumed for the tooth t' to a position such as is assumed for the tooth t^2 , the turning torques automatically become smaller and smaller until a balanced condition is obtained when the tooth is fully uprighted. Thus the applied forces vary in the right directions and in the right magnitudes as the corrective movements take place in the use

or wearing of the appliance, self-adjustment thereby continuously taking place.

Still viewing such figures as Figs. 8 to 10 of the drawing, it will be noted that each segment or loop is individual in action, that corrective movement of the tooth is determined by the orientation of the bracket and the interrelation between the loop of the arch wire therewith rather than upon any imparted distortion to the arch wire, the line or plane of the arch not being manually disturbed. It will also be noted that the corrective movement depends upon opposite action of the two component strands of the arch mechanism. This appliance also eliminates "jiggling" of the tooth since there is no unwarranted movement due to any action and reaction of a spring arch wire. The recoil of band and arch mechanisms incident to prior constructions is eliminated. There is complete control of pressure applied to each tooth. The force applied is determined by the relationship between the arch and the bracket button, predetermined by and inherent in the design and structure of these parts. The magnitude of the force is, of course, dependent upon the length of the bracket button, the length of the loop segment and the gauge of the arch wire; and suitable selections may be made depending upon the particular case presented by the patient.

Referring now again to Fig. 7 of the drawing, it will be seen how this orthodontic structure operates for producing other types of corrections. Both central incisors t' and t^2 are shown requiring axial orientation. From Fig. 7 it will be seen that the engagement of the strands of the arch wire with the button heads 30, 30 of the button brackets makes operative turning forces represented by the arrows 58 and 60 for effecting this desired correction. The same action takes place, that is, the engagement of the loop wire with the button head, for correcting for distal inclination. Where a tooth such as the second bicuspid t^3 requires a short bodily movement to arch aligning position, the arch wire may be directly connected to the button bracket as shown in Fig. 7; and here again the tension or pull is the result of the engagement of the strands of the loop with the head of the bracket button. Where, however, a tooth such as the second bicuspid t^4 requires a large bodily movement to arch aligning position as shown in Fig. 7, ligature wires may then be resorted to. To this end, the shank of the button is provided with the orifices 34, 34 heretofore referred to, and a ligature wire 62 is then used the same being threaded through these orifices to connect the bracket to the elements of the arch wire. It will be evident that for producing an elevation or depression movement towards the occlusion plane, the action of the arch wire will be one of tensioning engagement with one side (top or bottom) of the elements of the button. Thus the device is adapted for the various corrections met with in orthodontic practice.

The orthodontic appliance of the present invention, the manner of its use and the many advantages thereof in the technique of orthodontia will in the main be fully apparent from the above detailed description thereof. It will be further apparent that while I have described my invention in the preferred forms, changes may be made therein without departing from the spirit of the invention defined in the following claims.

I claim:

1. An orthodontic appliance comprising in

combination a button bracket attachable to a tooth, said button bracket having a button shank and a head, and a resilient and flexible arch wire provided with a resilient and flexible loop member, the said loop member being receivable by the button of said bracket, the loop member expanding as it is slipped over the head of the button and contracting itself into engagement with the shank of the button, the said loop member flexibly and resiliently acting on said button bracket to apply the corrective forces to the tooth.

2. An orthodontic appliance comprising in combination a band attachable to a tooth, a button bracket on said band, said button bracket having a button shank and a head, and a resilient and flexible arch wire provided with a resilient and flexible loop member, the said loop member being receivable by the button of said bracket, the loop member expanding as it is slipped over the head of the button and contracting itself into engagement with the shank of the button, the said loop member flexibly and resiliently acting on said button bracket to apply the corrective forces to the tooth.

3. The orthodontic appliance of claim 1 in which the button head and shank are elongated in a horizontal direction.

4. An orthodontic appliance comprising in combination a button bracket attachable to a tooth, said button bracket having a button shank and a head, and a resilient and flexible arch wire provided with a resilient and flexible loop member, the said loop member being receivable by the button of said bracket, the loop member expanding as it is slipped over the head of the button and contracting itself into engagement with the shank of the button, the said loop member having top and bottom strands flexibly and resiliently acting on opposite sides of the button shank but in the same rotative direction to correct for mesial inclination of the tooth.

5. An orthodontic appliance comprising in combination a band attachable to a tooth, a button bracket on said band, said button bracket having a button shank and a head, and a resilient and flexible arch wire provided with a resilient and flexible loop member, the said loop member being receivable by the button of said bracket, the loop member expanding as it is slipped over the head of the button and con-

tracting itself into engagement with the shank of the button, the said loop member having top and bottom strands flexibly and resiliently acting on opposite sides of the button shank but in the same rotative direction to correct for mesial inclination and acting on the button head to correct for distal inclination and to produce axis orientation of the tooth.

6. An orthodontic appliance comprising in combination a plurality of button brackets attachable to the teeth of a denture requiring correction, each of said button brackets having a button shank and a head, and a resilient and flexible arch wire comprising a series of connected resilient and flexible loop members, a loop member being individual to a bracket, each individual loop member being receivable by the button of its bracket, such loop member expanding as it is slipped over the head of the button and contracting itself into engagement with the shank of the button, such loop member flexibly and resiliently acting automatically on the shank or head or both of said button brackets to apply the corrective forces to the tooth, such as for mesial inclination, distal inclination, axis orientation, elevation or depression, and arch aligning, or for producing a combination of such corrections.

7. The orthodontic appliance of claim 6 in which the resilient and flexible arch wire comprises two parallel wire strands united at spaced intervals to form the series of connected loop members.

8. The orthodontic appliance of claim 6 in which the button head and shanks of the button brackets are elongated in a horizontal direction, and in which the shanks are perforated to receive ligature wires.

9. The orthodontic appliance of claim 6 in which the button head and shanks of the button brackets are elongated in a horizontal direction, and in which the resilient and flexible arch wire comprises two parallel wire strands united at spaced intervals to form the series of connected loop members.

10. In an orthodontic appliance, a resilient and flexible arch wire comprising two parallel wire strands united at spaced intervals to form a series of connected resilient and flexible loop members.

JOSEPH D. BERKE.
